[57] ABSTRACT

Cyclised benzylidene indenyl acetic acids and pharmaceutically acceptable salts, amides and esters thereof. The cyclised benzylidene indenyl acetic acids have anti-inflammatory, anti-pyretic and analgesic activity. The invention also includes methods for the preparation of these compounds, pharmaceutical compositions and methods of treating inflammation by administering these particular compounds to patients.

**CYCLOPENTA[J,K]-PHENANTHRENE-4-ACETIC
ACIDS AND RELATED COMPOUNDS**

SUMMARY OF THE INVENTION

This invention relates to novel cyclised benzylidene indenyl acetic acids and derivatives thereof, to pharmaceutical compositions, to a method of treating fever, pain and inflammation by employing these cyclised benzylidene indenyl acetic acids and to a process for 10 their preparation. The disclosed class of compounds of this invention exhibit anti-inflammatory activity and are effective in the prevention and inhibition of edema and granuloma tissue formation. They also possess a useful degree of anti-pyretic and analgesic activity. 15

BACKGROUND OF THE INVENTION

There has been much research carried on in the past two decades for development of anti-inflammatory drugs. As a result, a great many new drugs have been 20 synthesized. Most of these have been steroids of the 11-oxygenated pregnane series. These, while highly effective, have the drawback of causing many side effects. There has also been a concentrated effort in anti-inflammation research in the indole and indene series 25 with the result of many useful drugs. One particularly useful group of indene compounds are those disclosed in U.S. Pat. No. 3,654,349 issued Apr. 4, 1972.

I have found that certain cyclised benzylidene indenyl acetic acids are valuable anti-inflammatory agents. These cyclised benzylidene acetic acids are substantially different from prior art compounds in that they are cyclised benzylidene compounds containing four fused rings.

DESCRIPTION AND PREFERRED EMBODIMENTS

This invention relates to a class of chemical compounds which contain four fused rings and are derived from benzylidene indene compounds. The compounds are more specifically described by the following structural formula:

wherein:

R₁ and R₂ are each hydrogen or alkyl;
R₃ is hydrogen, alkyl, halo, haloalkyl, phenyl, alkylthio, phenylthio, alkenyl, alkoxyphenyl, trifluoromethyl or benzyl;
R₄, R₅ and R₆ are each hydrogen, alkyl, acyloxy, alkoxyl, acylamino, alkylamino, dialkylamino, dialkylaminoalkyl, sulfamyl, alkylthio, mercapto, hydroxy, hydroxyalkyl, alkenyl, alkenyloxy, alkylsulfinyl, alkylsulfonyl, dialkylsulfamyl, carboxyl, carboxy, carbamido, haloalkyl, cycloalkyl, phenyl, benzyl, benzylthio, phenoxy or cycloalkoxy;

R₇ is hydrogen, alkylthio, alkylsulfinyl or alkylsulfonyl;

R₈ is hydrogen, halo, hydroxy, alkoxy, haloalkyl, alkanoylamino or alkanoyl; and

M is hydroxy, loweralkoxy, loweralkenyloxy, benzylxy, substituted loweralkoxy, amino, alkylamino, dialkylamino, N-morpholino, hydroxyalkylamino, polyhydroxyalkylamino, dialkylaminoalkylamino, aminoalkylamino and the group OMe, in which Me is a cation; and their anhydrides.

In the still more preferred aspect of this invention:

R₁ and R₂ are each hydrogen;

R₃ is hydrogen, C₁₋₅ alkyl, halo, halo C₁₋₅ alkyl, phenyl, C₁₋₅ alkylthio, phenylthio, C₂₋₅ alkenyl, C₁₋₅ alkoxyphenyl, trifluoromethyl or benzyl;

R₄ is hydrogen, trifluoromethyl, halo, C₁₋₅ alkyl, phenyl, benzyl;

R₅ is hydrogen, hydroxy, halo, C₁₋₅ alkylthio, benzylxy, C₁₋₅ alkylsulfinyl, C₁₋₅ dialkylsulfonyl, C₁₋₅ dialkylamino-C₁₋₅ alkyl, C₁₋₅ alkylbenzyloxy, benzylthio, C₁₋₅ dialkylamino, halobenzyloxy, C₁₋₅ alkoxyl, C₁₋₅ alkyl, C₁₋₅ alkylsulfamyl, C₂₋₅ alkanoyloxy, phenoxy, C₂₋₅ alkenyl, C₂₋₅ alkenyloxy or benzyl;

R₆ is hydrogen, C₂₋₅ alkenyl, halo, C₁₋₅ alkoxy, C₁₋₅ alkyl, benzyloxy or C₁₋₅ alkylthio; at least one of R₄, R₅ or R₆ is hydrogen at any one time;

R₇ is hydrogen, C₁₋₅ alkylthio, C₁₋₅ alkylsulfinyl or C₁₋₅ alkylsulfonyl;

R₈ is hydrogen, halo, hydroxy, C₁₋₅ alkoxy, halo C₁₋₅ alkyl, phenyl, C₁₋₅ alkanoylamino or C₁₋₅ alkanoyl; and

M is hydroxy, C₁₋₅ alkoxy or pivalyloxy.

Still more particularly, the groups may be defined as follows:

R₁ and R₂ are each hydrogen;

R₃ is C₁₋₅ alkyl;

R₄ is hydrogen;

R₅ is hydrogen, C₁₋₅ dialkylamino, halo (chloro, fluoro, bromo), C₁₋₅ alkanoyloxy, C₂₋₅ alkenyl or C₂₋₅ alkenyloxy;

R₆ is hydrogen or halo (chloro, bromo, fluoro);

R₇ is halo (chloro, bromo, fluoro), C₁₋₅ alkylthio or C₁₋₅ alkylsulfinyl;

R₈ is hydrogen; and

M is hydroxy.

Representative compounds of the invention are:

2-fluoro-5-methyl-9-(p-methylthiobenzylidene)-cyclopenta [j,k]-phenanthrene-4-acetic acid,

2-fluoro-5-methyl-9-(p-methylsulfinylbenzylidene)-cyclopenta [j,k]-phenanthrene-4-acetic acid,

2-fluoro-5-methyl-9-(p-chlorobenzylidene)-cyclopenta [j,k]-phenanthrene-4-acetic acid,

2-fluoro-5-methyl-9-(p-fluorobenzylidene)-cyclopenta [j,k]-phenanthrene-4-acetic acid,

2-fluoro-5-methyl-9-(m-hydroxybenzylidene)-cyclopenta [j,k]-phenanthrene-4-acetic acid,

2-fluoro-5-methyl-9-(m-methoxybenzylidene)-cyclopenta [j,k]-phenanthrene-4-acetic acid,

2-fluoro-5-methyl-9-(m-methylsulfinylbenzylidene)-cyclopenta [j,k]-phenanthrene-4-acetic acid,

2-fluoro-5-methyl-9-(m-phenylbenzylidene)-cyclopenta [j,k]-phenanthrene-4-acetic acid,

2-fluoro-5-methyl-9-(o-acetamidebenzylidene)-cyclopenta [j,k]-phenanthrene-4-acetic acid,

2-fluoro-5-methyl-9-(o-acetylbenzylidene)-cyclopenta [j,k]-phenanthrene-4-acetic acid,

2-methyl-5-methyl-9-(p-methylsulfinylbenzylidene)-cyclopenta [j,k]-phenanthrene-4-acetic acid,
 2-hydroxy-5-methyl-9-(p-methylsulfinylbenzylidene)-cyclopenta [j,k]-phenanthrene-4-acetic acid,
 2-methylthio-5-methyl-9-(p-methylsulfinylbenzylidene)-cyclopenta [j,k]-phenanthrene-4-acetic acid,
 2-benzyloxy-5-methyl-9-(p-methylsulfinylbenzylidene)-cyclopenta [j,k]-phenanthrene-4-acetic acid,
 2-diethylamino-5-methyl-9-(p-methylsulfinylbenzylidene)-cyclopenta [j,k]-phenanthrene-4-acetic acid,
 1,2-difluoro-5-methyl-9-(p-methylsulfinylbenzylidene)-cyclopenta [j,k]-phenanthrene-4-acetic acid,
 2-methoxy-5-methyl-9-(p-methylsulfinylbenzylidene)-cyclopenta [j,k]-phenanthrene-4-acetic acid,
 2-methyl-5-methyl-9-(p-methylsulfinylbenzylidene)-cyclopenta [j,k]-phenanthrene-4-acetic acid,
 2-vinyl-5-methyl-9-(p-methylsulfinylbenzylidene)-cyclopenta [j,k]-phenanthrene-4-acetic acid,
 1-methyl-5-methyl-9-(p-methylsulfinylbenzylidene)-cyclopenta [j,k]-phenanthrene-4-acetic acid,
 2-vinylxylo-5-methyl-9-(p-methylsulfinylbenzylidene)-cyclopenta [j,k]-phenanthrene-4-acetic acid,
 2-acetyloxy-5-methyl-9-(p-methylsulfinylbenzylidene)-cyclopenta [j,k]-phenanthrene-4-acetic acid,
 2-fluoro-5-methyl-9-(p-methylthiobenzylidene)-cyclopenta [j,k]-phenanthrene-4- α -propionic acid,
 2-fluoro-5-methyl-9-(p-methylsulfinylbenzylidene)-cyclopenta [j,k]-phenanthrene-4- α -propionic acid,
 2-fluoro-5-methyl-9-(p-chlorobenzylidene)-cyclopenta [j,k]-phenanthrene-4- α -propionic acid,
 2-fluoro-5-methyl-9-(p-fluorobenzylidene)-cyclopenta [j,k]-phenanthrene-4- α -propionic acid,
 2-fluoro-5-methyl-9-(m-hydroxybenzylidene)-cyclopenta [j,k]-phenanthrene-4- α -propionic acid,
 2-fluoro-5-methyl-9-(m-methoxybenzylidene)-cyclopenta [j,k]-phenanthrene-4- α -propionic acid,
 2-fluoro-5-methyl-9-(m-methylsulfinylbenzylidene)-cyclopenta [j,k]-phenanthrene-4- α -propionic acid,
 2-fluoro-5-methyl-9-(m-phenylbenzylidene)-cyclopenta [j,k]-phenanthrene-4- α -propionic acid,
 2-fluoro-5-methyl-9-(o-acetamidebenzylidene)-cyclopenta [j,k]-phenanthrene-4- α -propionic acid,
 2-fluoro-5-methyl-9-(o-acetylbenzylidene)-cyclopenta [j,k]-phenanthrene-4- α -propionic acid,
 2-methyl-5-methyl-9-(p-methylsulfinylbenzylidene)-cyclopenta [j,k]-phenanthrene-4- α -propionic acid,
 2-hydroxy-5-methyl-9-(p-methylsulfinylbenzylidene)-cyclopenta [j,k]-phenanthrene-4- α -propionic acid,
 2-methylthio-5-methyl-9-(p-methylsulfinylbenzylidene)-cyclopenta [j,k]-phenanthrene-4- α -propionic acid,
 2-benzyloxy-5-methyl-9-(p-methylsulfinylbenzylidene)-cyclopenta [j,k]-phenanthrene-4- α -propionic acid,
 2-diethylamino-5-methyl-9-(p-methylsulfinylbenzylidene)-cyclopenta [j,k]-phenanthrene-4- α -propionic acid,

1,2-difluoro-5-methyl-9-(p-methylsulfinylbenzylidene)-cyclopenta [j,k]-phenanthrene-4- α -propionic acid,
 2-methoxy-5-methyl-9-(p-methylsulfinylbenzylidene)-cyclopenta [j,k]-phenanthrene-4- α -propionic acid,
 2-methyl-5-methyl-9-(p-methylsulfinylbenzylidene)-cyclopenta [j,k]-phenanthrene-4- α -propionic acid,
 2-vinyl-5-methyl-9-(p-methylsulfinylbenzylidene)-cyclopenta [j,k]-phenanthrene-4- α -propionic acid,
 1-methyl-5-methyl-9-(p-methylsulfinylbenzylidene)-cyclopenta [j,k]-phenanthrene-4- α -propionic acid,
 2-vinylxylo-5-methyl-9-(p-methylsulfinylbenzylidene)-cyclopenta [j,k]-phenanthrene-4- α -propionic acid,
 2-acetyloxy-5-methyl-9-(p-methylsulfinylbenzylidene)-cyclopenta [j,k]-phenanthrene-4- α -propionic acid.

The compounds of the instant invention can be used to treat inflammation by reducing inflammation and relieving pain in such diseases as rheumatoid arthritis, osteoarthritis, gout, infectious arthritis and rheumatic fever. The compounds of the invention can also be used as an anti-pyretic and would be administered and used in the same manner and in the same dosage ranges as if they were being used to treat inflammation as discussed further on.

The treatment of inflammation in accordance with the method of the present invention is accomplished by topically, orally, rectally or parenterally administering to patients a composition of a compound of the invention, particularly the especially preferred compounds, in a non-toxic pharmaceutically acceptable carrier.

The non-toxic pharmaceutical carrier may be, for example, either a solid or a liquid. Exemplary of solid carriers are lactose, corn starch, gelatin, talc, sterotix, stearic acid, magnesium stearate, terra alba, sucrose, agar, pectin, cab-o-sil and acacia. Exemplary of liquid carriers are peanut oil, olive oil, sesame oil and water. Similarly, the carrier or diluent may include a time delay material such as glyceryl monostearate or glyceryl distearate alone or with a wax.

Several pharmaceutical forms of the therapeutically useful compositions can be used. For example, if a solid carrier is used, the compositions may take the form of tablets, capsules, powders, troches or lozenges, prepared by standard pharmaceutical techniques. If a liquid carrier is used, the preparation may be in the form of a soft gelatin capsule, a syrup, an aqueous solution or a liquid suspension. Suppositories may be prepared in a conventional manner by mixing the compounds of this invention with a suitable non-irritating excipient which is solid at room temperature, but liquid at the rectal temperature. Such materials are cocoa butter and polyethylene glycol. Gels and lotions for topical application may be prepared in conventional manners.

The compounds of this invention are to be administered in an amount sufficient to treat inflammation, that is, to reduce inflammation. Advantageously, the compositions will contain the active ingredient; namely, the compounds of the invention in an amount of from about 0.1 mg. to 50 mg. per kg. body weight per day (5 mg. to 3.5 g. per patient per day), preferably from about 1 mg. to 15 mg./kg. body weight per day (50 mg. to 1 g. per patient per day).

The method of treatment of this invention comprises administering to a patient (animal or human), a com-

pound of the invention particularly an especially preferred compound admixed with a non-toxic pharmaceutical carrier such as exemplified above. The compounds and particularly the especially preferred compounds will be administered in an amount of from 0.1 mg. to 50 mg./kg. body weight per day, preferably from about 1 mg. to about 15 mg. per kilogram body weight per day. The most rapid and effective anti-inflammatory effect is obtained from oral administration of a daily dosage of from about 1 to 15 mg./kg./day. It should be understood, however, that although preferred dosage ranges are given, the dose level for any particular patient depends upon the activity of the specific compound employed. Also, many other factors that modify the actions of drugs will be taken into account by those skilled in the art in the therapeutic use of medicinal agents, for example, age, body weight, sex, diet, time of administration, route of administration, rate of excretion, drug combination, reaction sensitivities and severity of the particular disease.

The compounds of this invention may be prepared by cyclising a 7-iodo-1-(2'-iodobenzylidene)-3-indenyl-3-aliphatic acid compound of the formula:

The cyclization may be carried out by any well known means for ring formation such as by reaction with metals and metal compounds, i.e., cuprous oxide, copper powder, copper bronze or zinc powder. Preferably, the reaction is carried out at temperatures of from 150° to 300° in the presence of an alkali such as potassium carbonate or sodium carbonate using an inert solvent such as nitrobenzene, dimethyl formamide, N-methylpyrrolidinone or amyl alcohol. The compound of Formula II in turn may be prepared by condensation of a 7-iodo-indenyl-3-aliphatic acid compound with a 2-iodobenzaldehyde compound under condensation conditions well known to the art such as reaction of these compounds in the presence of trimethylammonium hydroxide, sodium methoxide or sodium hydride in the presence of solvents such as methanol, ethanol or benzene at temperatures of from 0° to 100°.

The 7-iodo-indenyl-3-aliphatic acid compound may be prepared by nitrosation of known indanone compounds, for example, by reaction with sodium nitrite or potassium nitrite in dilute acids in the presence of potassium iodide or cuprous iodide at temperatures of 0° to 50°. The nitroindanone compound is then converted

to the corresponding aminoindanone compound by methods well known to the art for converting a nitro group to an amino group such as by reaction with tin and hydrochloric acid or zinc and acetic acid or catalytically with Raney nickel in ethyl acetate and acetic acid at temperatures of from 20° to 50°. The aminoindanone compound in turn is converted to the 7-iodoindenyl-3-aliphatic acid compound by reaction with a haloaliphatic acid or ester in the presence of zinc in an inert solvent such as benzene or toluene at reflux temperatures.

The 2-iodobenzaldehyde compound may be readily prepared from anthranilic acid compounds by converting the anthranilic acid compound to its corresponding iodobenzoic acid compound in a manner described previously for converting the aminoindanone compound to the 7-iodoindanone compound. The iodobenzoic acid compound is then converted to the corresponding iodobenzaldehyde by well known methods for converting a carboxylic acid group to the aldehydohydro group. For example, the iodobenzoic acid compound may be treated with an appropriate halide such as thionyl halide, sulfinyl halide or phosphorous pentahalide in the presence of a solvent such as benzene, toluene, hexane or tetrahydrofuran at a temperature of from 25° to 100° to form the corresponding acid halide. This latter compound is then converted to the corresponding nitrile by reaction with ammonia, then with phosphorous pentoxide or concentrated sulfuric acid in the presence of benzene or polyphosphoric acid as solvent at a temperature of from 50° to 150°. The above nitrile is then refluxed, for example, with Raney nickel or nickel amalgam in 80% formic or acetic acids at temperatures of 100° to 150° to form the desired iodobenzaldehyde.

The following examples are given by way of illustration:

EXAMPLE 1

4-Methylthio-2-indobenzaldehyde

A. 4-Methylthio-2-nitrobenzoic acid

4-Chloro-2-nitrobenzoic acid (prepared as described in *Helv. Chim. Acta.* 45 371 (1957) and *J. Org. Chem.* 22 639 (1957) (0.3. mole) is added in methanol (100 ml.) to a solution of methylmercaptan bubbled into sodium methoxide (fresh, 0.4 mole) in methanol (300 ml.) that was saturated. The addition was slow and when all had been added the solution is refluxed for 2 hours under nitrogen. It is then evaporated to near dryness and the acid precipitated with dilute hydrochloric acid. The solid is filtered and used as is.

B. 4-Methylthioanthranilic acid

The above nitro compound (0.2 mole) is catalytically reduced with 10% Pd/C in ethyl acetate (1 l.) at 40 p.s.i. and room temperature until the theoretical amount of hydrogen was taken up. The catalyst was filtered off and the solution evaporated to dryness to give the 4-methylthioanthranilic acid.

C. 4-Methylthio-2-iodobenzoic acid

The above anthranilic acid (0.5 mole) is refluxed in 4N hydrochloric acid (2 l.) for 1 hour and is then filtered and cooled to 0°. A solution of sodium nitrite (0.6 ml.) in water (200 ml.) at 0° is slowly added with stirring so that the temperature does not rise above 5°. This solution is added at 0°-10° to a solution of potassium iodide (0.6 mole) in water (120 ml.) with stirring.

The reaction is slowly brought to reflux and kept there for 1 hour. The reaction is cooled and made acid. 4-methylthio-2-iodobenzoic acid is extracted into ether (4 × 200 ml.) and the ether layer washed with water (2 × 100 ml.) and dried ($MgSO_4$). The ether solution is filtered and evaporated to dryness to give solid 4-methylthio-2-iodobenzoic acid which can be recrystallized from benzene.

D. 4-Methylthio-2-iodobenzoyl chloride

The above benzoic acid (0.2 mole) is refluxed in thionyl chloride (200 ml.) with three drops of dimethylformamide for 1 hour and then evaporated to dryness and pumped out under very high vacuum. The crude product is used as is.

E. 4-Methylthio-2-iodobenzonitrile

The above acid chloride (0.3 mole) in water (200 ml.) at 0° is added over 10 minutes to a stirred solution of concentrated ammonium hydroxide (200 ml.). After 2 hours the solution is evaporated to dryness.

The powdered product is heated and stirred in benzene (300 ml.) and phosphorous pentoxide (1 mole) for 3 hours. The reaction mixture is cooled, filtered and the filtrate washed well with cold N. sodium hydroxide solution (3 × 100 ml.), water (2 × 50 ml.) and then dried ($MgSO_4$). The filtrate solution is evaporated to dryness to give 4-methylthio-2-iodobenzonitrile.

F. 4-Methylthio-2-iodobenzaldehyde

The above nitrile (0.3 mole) is stirred and refluxed in 80% formic acid (200 ml.) while nickel-aluminum amalgam (1:1 Maleinckdrot 2 mole) is added over 2 hours. The solution is then filtered, the filtrate evaporated to dryness, taken up in benzene (200 ml.) and washed with water (2 × 50 ml.). The organic layer is dried ($MgSO_4$) and filtered. The filtrate is evaporated to dryness and carefully distilled under 0.001 mm. of H_2 pressure to give a pure fraction of 4-methylthio-2-iodobenzaldehyde.

Similarly, when

4-methylanthranilic acid,
4-bromoanthranilic acid,
4-chloroanthranilic acid,
4-fluoroanthranilic acid,
4-hydroxyanthranilic acid,
4-methylsulfinylanthranilic acid,
5-bromoanthranilic acid,
5-chloroanthranilic acid,
5-fluoroanthranilic acid,
5-hydroxyanthranilic acid,
5-methoxyanthranilic acid,
5-methylsulfinylanthranilic acid,
5-methylanthranilic acid,
5-phenylanthranilic acid,
3-hydroxyanthranilic acid,
3-methylanthranilic acid,
6-methylanthranilic acid,
6-acetamidoanthranilic acid,
6-acetylanthranilic acid, or
anthranilic acid

is used in place of 4-methylthioanthranilic acid in Example 1 C above and the corresponding substituted 2-iodobenzoic acid compound carried through Steps 1 a-f, there is obtained the correspondingly substituted 2-iodobenzaldehyde

EXAMPLE 2

Methyl-5-fluoro-7-iodo-2-methylindenyl-3-acetate
A. 6-Fluoro-4-nitro-2-methylindanone

A solution of potassium nitrate (0.2 mole) in concentrated sulfuric acid (300 ml.) is added slowly to a solution of 6-fluoro-2-methylindanone (0.18 mole) in concentrated sulfuric acid (40 ml.) at 10° with stirring in an ice-alcohol cooling bath. At the end of the addition the solution is brought to room temperature, stirred for 2 hours and poured carefully into ice (2 l.) with stirring. The organic layer is extracted into ether (2 × 1 l.), dried ($MgSO_4$), filtered and the filtrate evaporated to dryness. The residual oil is fractionally distilled at 0.001 mm. Hg pressure and the final pure factor of 6-fluoro-4-nitro-2-methylindanone isolated and characterized by analysis and nuclear magnetic resonance spectroscopy.

15 B. 4-Amino-6-fluoro-2-methylindanone

The above nitro compound (0.15 mole) is catalytically hydrogenated over Raney nickel (0.5 teaspoonful) in ethyl acetate (200 ml.) and glacial acetic acid (20 ml.) at 40 p.s.i. and room temperature until the 20 theoretical amount of hydrogen (0.45 mole) had been taken up. The catalyst is filtered off, the solvent evaporated to near dryness, the residue taken up in ethyl acetate (200 ml.) and washed well with saturated sodium bicarbonate solution (2 × 40 ml.). The organic layer 25 is dried ($MgSO_4$) and filtered. The filtrate is evaporated to dryness and the amine used as is.

C. 6-Fluoro-4-iodo-2-methylindanone

The above amine (0.7 mole) is dissolved in 4 N. hydrochloric acid (300 ml.) and cooled well to 0°. A solution of sodium nitrite (0.9 mole) in water (100 ml.) at 30 0° is added slowly with stirring so that the temperature does not rise above 0°-10°. To this solution is added a solution of potassium iodide (0.9 mole) in water (200 ml.) at 0°-10°. The reaction mixture is then stirred well 35 for 2 hours and gradually brought up to 60° and kept there until the nitrogen emission ceases.

The organics are then extracted with ethyl acetate (2 × 400 ml.), the organic layer washed with water (2 × 100 ml.), separated and dried ($MgSO_4$). The solution 40 is filtered and evaporated to dryness. The oil is fractionally distilled at 0.001 mm. pressure to get pure 6-fluoro-4-iodo-2-methylindanone.

Similarly when the following indanones are used in 45 place of 6-fluoro-2-methylindanone in Example 2 A above and the product therefrom carried through Example 2 B-C, there is obtained the corresponding substituted 4-iodoindanones:

2-methylindanone,
6-fluoroindanone,
2,6-dimethylindanone,
2-methyl-6-hydroxyindanone,
2-methyl-6-methylthioindanone,
2-methyl-6-benzoyloxyindanone,
2-methyl-6-methylsulfonylindanone,
2-methyl-6-dimethylsulfonylindanone,
2-methyl-6-dimethylaminoethylindanone,
2-methyl-6-(p-ethylbenzoyloxy)indanone,
2-methyl-6-fluoroindanone,
2-methyl-6-benzylthioindanone,
2-methyl-6-diethylaminoindanone,
2-methyl-6-(p-chlorobenzoyloxy)indanone,
2-methyl-5,6-methylenedioxyindanone,
2-methyl-5,6-difluoroindanone,
2-methyl-5-fluoro-6-methoxyindanone,
2-isopropyl-6-methoxyindanone,
2-phenyl-6-methylindanone,
2-methylthio-6-methylindanone,

2-phenylthioindanone,
2-allyl-6-methoxyindanone,
2-fluoroindanone,
2-chloromethyl-6-dimethylsulfamylindanone,
2-(p-methoxyphenyl)-6-t-butylindanone,
2-trifluoromethyl-6-ethoxyindanone,
2-(t-butyl)-6-methoxy-7-trifluoromethylindanone,
2-(p-methoxyphenyl)-5-chloro-6-methoxyindanone,
6-vinylindanone,
5-methoxyindanone,
6-methoxyindanone,
6-methyl-2-benzylindanone,
5-methylindanone,
5-methyl-6-methoxyindanone,
2-methyl-6-vinyloxyindanone,
2-methyl-6-acetoxyindanone,
5-methyl-7-chloroindanone,
7-phenylindanone,
2-phenylindanone,
6,7-benzoindanone,
5,6,7-trichloroindanone,
5-benzylxyindanone,
2-n-butylindanone, and
5-methylthioindanone

D. Methyl 5-fluoro-7-iodo-2-methylindenyl-3-acetate

A solution of 0.075 mole of 6-fluoro-4-iodo-2-methylindanone and 0.075 mole of methyl bromoacetate in 45 ml. benzene is added over a period of 5 minutes to 21 g. of zinc amalgam (prepared according to Org. Syn. Coll., vol. 3) in 110 ml. benzene and 40 ml. dry ether. A few crystals of iodine are added to start the reaction, and the reaction mixture is maintained at reflux temperature (ca. 65°) with external heating. At 3 hour intervals two batches of 10 g. zinc amalgam and 10 g. bromoester are added and the mixture is then refluxed for 8 hours. After addition of 30 ml. of ethanol and 150 ml. of acetic acid, the mixture is poured into 700 ml. of 1:1 aqueous acetic acid. The organic layer is separated, and the aqueous layer is extracted twice with ether. The combined organic layers are washed thoroughly with water, ammonium hydroxide and water. Drying over sodium sulfate, evaporation of solvent in *vacuo* gives crude methyl (1-hydroxy-2-methyl-4-iodo-6-fluoro-indenyl) acetate.

A mixture of the above crude hydroxyester, 20 g. of p-toluenesulfonic acid monohydrate and 20 g. of anhydrous calcium chloride in 250 ml. toluene is refluxed overnight. The solution is filtered and the solid residue is washed with benzene. The combined benzene solution is washed with water, sodium bicarbonate, water and then dried over sodium sulfate. After evaporation the crude methyl 5-fluoro-4-iodo-2-methyl-3-indenylacetate is chromatographed on acid-washed alumina, and the product is eluted with petroleum ether-ether (v.v. 50-100%).

Similarly when the substituted 4-iodoindanones obtained from Example 2 C above are used in place of 6-fluoro-4-iodo-2-methylindanone in the above example, there is obtained the corresponding substituted 7-iodoindenyl-3-acetate compounds.

Similarly when
2-methylindanone,
6-fluoroindanone,
2,6-dimethylindanone,
2-methyl-6-hydroxyindanone,
2-methyl-6-methylthioindanone,
2-methyl-6-benzylxyindanone,

5-methyl-6-methoxyindanone,
5-methyl-7-chloroindanone,
7-phenylindanone,
2-phenylindanone,
6,7-benzoindanone,
5,6,7-trichloroindanone,
5-benzylxyindanone,
2-n-butylindanone, and
5-methylthioindanone

are used in place of 6-fluoro-2-methylindanone in Example 2 A and the product carried out through Steps B-D, there is obtained the corresponding substituted 7-iodo-indenyl 3-acetate compounds.

EXAMPLE 3

5-Fluoro-7-iodo-2-methylindenyl-3- α -propionate

A solution of 0.075 mole of 6-fluoro-4-iodo-2-methylindanone and 0.075 mole of methyl- α -bromopropionate in 45 ml. benzene is added over a period of 5 minutes to 21 g. of zinc amalgam (prepared according to Org. Syn. Coll., vol. 3) in 110 ml. benzene and 40 ml. dry ether. A few crystals of iodine are added to start the reaction, and the reaction mixture is maintained at reflux temperature (ca. 65°) with external heating. At 3 hour intervals two batches of 10 g. zinc amalgam and 10 g. bromoester are added and the mixture is then refluxed for 8 hours. After addition of 30 ml. of ethanol and 150 ml. of acetic acid, the mixture is poured into 700 ml. of 1:1 aqueous acetic acid. The organic layer is separated, and the aqueous layer is extracted twice with ether. The combined organic layers are washed thoroughly with water, ammonium hydroxide and water. Drying over sodium sulfate, evaporation of solvent in *vacuo* gives crude methyl (1-hydroxy-2-methyl-4-iodo-6-fluoro-indenyl)- α -propionate.

A mixture of the above crude hydroxyester, 20 g. of p-toluenesulfonic acid monohydrate and 20 g. of anhydrous calcium chloride in 250 ml. toluene is refluxed overnight. The solution is filtered and the solid residue is washed with benzene. The combined benzene solu-

tion is washed with water, sodium bicarbonate, water and then dried over sodium sulfate. After evaporation the crude methyl 5-fluoro-4-iodo-2-methyl-3-indenyl- α -propionate is chromatographed on acid-washed alumina, and the product is eluted with petroleum ether-ether (v.v. 50-100%).

Similarly when the substituted 4-iodoindanones obtained from Example 2 C above are used in place of 6-fluoro-4-iodo-2-methylindanone in Example 2 C above, there is obtained the corresponding substituted 7-iodoindenyl-3-acetate compounds.

Similarly when

2-methylindanone,
6-fluoroindanone,
2,6-dimethylindanone,
2-methyl-6-hydroxyindanone,
2-methyl-6-methylthioindanone,
2-methyl-6-benzoyloxyindanone,
2-methyl-6-methylsulfonylindanone,
2-methyl-6-dimethylsulfonylindanone,
2-methyl-6-dimethylaminoethylindanone,
2-methyl-6-(p-ethylbenzyloxy)indanone,
2-methyl-6-fluoroindanone,
2-methyl-6-benzylthioindanone,
2-methyl-6-diethylaminoindanone,
2-methyl-6-(p-chlorobenzyloxy)indanone
2-methyl-5,6-methylenedioxyindanone,
2-methyl-5,6-difluoroindanone,
2-methyl-5-fluoro-6-methoxyindanone,
2-isopropyl-6methoxyindanone,

2-methylthio-6-methylindanone,
2-phenylthioindanone,
2-allyl-6-methoxyindanone,
2-fluoroindanone,
2-chloromethyl-6-dimethylsulfamylindanone,
2-(p-methoxyphenyl)-6-t-butylindanone,
2-trifluoromethyl-6-ethoxyindanone,
2-(t-butyl)-6-methoxy-7-trifluoromethylindanone,
2-(p-methoxyphenyl)-5-chloro-6-methoxyindanone,
6-vinylindanone,
5-methoxyindanone,
6-methoxyindanone,
6-methyl-2-benzylindanone,
5-methylindanone,
5 methyl-6-methoxyindanone,
5-methyl-7-chloroindanone,
7-phenylindanone,
2-phenylindanone,
6,7-benzoindanone,
5,6,7,-trichloroindanone,
5-benzoyloxyindanone,
2-n-butylindanone, and
5-methylthioindanone

are used in place of 6-fluoro-2-methylindanone in Example 2 A and the product carried out through Steps B-D, there is obtained the corresponding substituted 7-iodo-indenyl-3-acetate compounds.

EXAMPLE 4

5-Fluoro-7-iodo-2-methyl-1-(2'-ido-4'-methylthiobenzylidene)-indenyl-3-acetic acid

To a solution of (0.00192 mole) of methyl-5-fluoro-7-iodo-2-methylindenyl-3-acetate and (0.0039 mole) of 2-ido-4-methylthiobenzaldehyde in 3 ml. of anhydrous pyridine is added 1.63 gm. of a 40% solution of benzyltrimethylammonium hydroxide in methanol. The

resultant reaction is allowed to stir at room temperature overnight. The reaction mixture is poured into a mixture of ice and water, acidified with 2.5N HCl and extracted with ether. The ether solution is then washed with 2.5N HCl until the washing acidifies, then with water until neutral. The ether layer is then extracted with 5% Na₂CO₃ solution. The Na₂CO₃ solution is washed with ether, acidified and extracted with ether. The ether solution is washed with water, dried over Na₂SO₄ and concentrated in vacuo to yield crude product.

Similarly when the substituted 7-iodoindenyl-3-acetate compounds obtained from Example 3 are used in place of methyl-5-fluoro-7-ido-2-methylindenyl-3-acetate in the above example, there is obtained the corresponding substituted 7-ido-1-(2'-ido-4'-methylthiobenzylidene)-indenyl-3-acetic acid.

Similarly when the substituted 2-iodobenzaldehyde compounds obtained from Example 1 are used in place of 2-ido-4-methylthiobenzaldehyde in the above example, there are obtained the corresponding 5-fluoro-7-ido-2-methyl-1-(substituted 2'-iodobenzylidene)indenyl-3-acetic acid compounds.

Similarly when the substituted 2-iodobenzaldehyde compounds obtained from Example 1 are used in place of 2-ido-4-methylthiobenzaldehyde and the substituted 7-iodoindenyl-3-acetate compounds obtained from Example 3 are used in place of methyl-5-fluoro-7-ido-2-methylindenyl-3-acetate in the above example, there is obtained the corresponding 7-ido-1-(substituted 2'-indobenzylidene)-indenyl-3-acetic acid compounds.

Similarly when 5-fluoro-7-ido-2-methylindenyl-3- α -propionate is used in the above example in place of 5-fluoro-7-ido-2-methylindenyl-3-acetate, there is obtained 5-fluoro-7-ido-2-methyl-1-(2'-ido-4'-methylthiobenzylidene)-indenyl-3- α -propionic acid

EXAMPLE 5

2-Fluoro-5-methyl-9-(p-methylthiobenzylidene)-cyclopenta[j,k]-phenanthrene-4-acetic acid

The above compound (0.1 mole) in ethyl acetate-alcohol (1:1 200 ml.) is esterified with excess diazomethane at 10° and the excess diazomethane and solvent evaporated off at room temperature. The crude ester (0.09 mole) is then mixed with tetraglyme (50 ml.), bright copper powder (50 gm.) and heated and stirred at 200° under nitrogen for 72 hours while more copper powder is added during the reaction (5 gm.). After this time the tetraglyme solution is filtered and warmed with aqueous sodium hydroxide (2.5N, 200 ml.) and alcohol (200 ml.) The alcohol is evaporated off and the aqueous solution extracted with ether (3 $\times$ 200 ml.). The aqueous solution is acidified and extracted into ethyl acetate (2 $\times$ 100 ml.). The ethyl acetate is dried (MgSO₄), filtered and the filtrate evaporated to dryness. The residue is dissolved in methanol (100 ml.) and refluxed with 0.5 ml. concentrated sulfuric acid for 2 hours. The solution is evaporated to 5 ml. dissolved in saturated sodium bicarbonate (100 ml) and extracted with ether (3 $\times$ 50 ml.). The ether layers are separated, combined and dried (MgSO₄). The filtrate is evaporated to dryness and chromatographed on a column of silica-gel (3 ft. $\times$ 2 in.) using proportions of ether-n-hexane as eluants over ether-alcohol.

A pure fraction of methyl 2-fluoro-5-methyl-9-(p-methylthiobenzylidene)-cyclopenta[j,k]-phenanthrene-4-acetate is obtained. This is refluxed in aqueous alcohol 2.5N. sodium hydroxide solution (1:1 100 ml.) for 1 hour under nitrogen. The alcohol is evaporated off and the residual aqueous layer extracted with ether (2 × 100 ml.), separated and residual ether pumped away and acidified with 2.5 N. hydrochloric acid. The solid acid is precipitated and collected, washed well with water and dried in the oven at 40° over phosphorus pentoxide and under vacuum.

Similarly when the substituted 7-iodo-(2'-iodo-4'-methylthiobenzylidene)-indenyl-3-acetic acid compounds, 5-fluoro-7-iodo-2-methyl-1-(substituted 2'-iodo-benzylidene)-indenyl-3-acetic acid compounds and the substituted 7-iodo-1-(substituted 2'-iodobenzylidene)-indenyl-3-acetic acid compounds obtained from Example 4 are used in place of 5-fluoro-7-iodo-2-methyl-1-(2'-iodo-4'-methylthiobenzylidene)-indenyl-3-acetic acid in the above example, there is obtained the corresponding substituted 9-(p-methylthiobenzylidene)-cyclopenta[j,k]-phenanthrene-4-acetic acid compounds, 2-fluoro-5-methyl-9-(substituted benzylidene)-cyclopenta[j,k]-phenanthrene-4-acetic acid compounds and substituted 9-(substituted benzylidene)-cyclopenta[j,k]-phenanthrene-4-acetic acid compounds, respectively.

Similarly when 5-fluoro-7-iodo-2-methyl-1-(2'-iodo-phenanthrene-methylthiobenzylidene)-indenyl-3- α -propionic acid obtained from Example 4 above is used in place of 5-fluoro-7-iodo-2-methyl-1-(2'-iodo-4'-methylthiobenzylidene)-indenyl-3-acetate, there is obtained 2-fluoro-5-methyl-9-(p-methylthiobenzylidene)-cyclopenta[j,k]-phenanthrene-4- α -propionic acid.

EXAMPLE 6

2-Fluoro-5-methyl-9-(p-methylsulfinylbenzylidene)cyclopenta[j,k]-phenanth-

rene-4-acetic acid

2-Fluoro-5-methyl-9-(p-methylthiobenzylidene)cyclopenta[j,k]-phenanthrene-4-acetic acid (0.2 mole) is stirred in solution at room temperature in acetone (700 ml.) and water (100 ml.) while sodium metaperiodate (0.25 mole) in water (100 ml.) is added over 2 hours. The oxidation of the thio ether to a sulfinyl residue can be followed by thin layer chromatography by taking 0.01 ml. aliquots at certain times from the reaction mixture and putting them on 6 in. × 2 in. 250 μ silica-gel chromatoplates and observing the elution with ethyl acetate. The sulfinyl compound runs with a lower R_f . When the reaction is observed to be complete (can be anytime from 2 hours to 3 days) the reaction mixture is evaporated to 300 ml. under high vacuum at 10°. The organics are extracted into ethyl acetate (3 × 300 ml.), dried ($MgSO_4$), filtered and evaporated to dryness. The residue solidifies and has the 9.8 μ peak in its infrared spectrum indicating the sulfinyl residue.

Similarly when 2-fluoro-5-methyl-9-(p-methylthiobenzylidene)-cyclopenta[j,k]-phenanthrene-4- α -propionic acid obtained from Example 3 is used in place of 2-fluoro-5-methyl-9-(p-methylthiobenzylidene)-cyclopenta[j,k]-phenanthrene-4-acetic acid in the above example, there is obtained the corresponding methylsulfinyl compound.

EXAMPLE 7

The following further specific special products (Column L) are obtained by employing the starting material under Column A below in Example 1 A to F to obtain the aldehyde compound as indicated in Column F below and reacting said aldehyde with the product obtained by reacting a compound under Column G below in Example 2 A to D to obtain the indene of Column J. The products of Column J is then reacted in accordance to Examples 4 and 5 to obtain the product of Column L.

A. STARTING MATERIAL	F. PRODUCT	G. STARTING MATERIAL	J. PRODUCT	L. PRODUCT
1. 4-Fluoro-2-nitrobenzoic acid	4-Fluoro-2-iodobenzaldehyde	5-Fluoro-2-methylindanone	Methyl 6-fluoro-7-iodo-2-methylindenyl-3-acetate	1-Fluoro-5-methyl-9-(p-fluorobenzylidene)-cyclopenta[j,k]-phenanthrene-4-acetic acid
2. 4-Chloro-2-nitrobenzoic acid	4-Methylthio-2-iodobenzaldehyde	6-Cyano-2-methylindanone	Methyl 5-cyano-7-iodo-2-methylindenyl-3-acetate	2-Cyano-5-methyl-9-(p-methylthiobenzylidene)-cyclopenta[j,k]-phenanthrene-4-acetic acid
3. 4-Chloro-2-nitrobenzoic acid	4-Methylthio-2-iodobenzaldehyde	6-Dimethylamino-2-methylindanone	Methyl 5-dimethylamino-7-iodo-2-methylindenyl-3-acetate	2-Dimethylamino-5-methyl-9-(p-methylthiobenzylidene)-cyclopenta[j,k]-phenanthrene-4-acetic acid
4. 4-Chloro-2-nitrobenzoic acid	4-Methylthio-2-iodobenzaldehyde	6-Allyloxy-2-methylindanone	Methyl 5-allyloxy-7-iodo-2-methylindenyl-3-acetate	2-Allyloxy-5-methyl-9-(p-methylthiobenzylidene)-cyclopenta[j,k]-phenanthrene-4-acetic acid
5. 4-Chloro-2-nitrobenzoic acid	4-Methylthio-2-iodobenzaldehyde	6-Chloro-2-methylindanone	Methyl 5-chloro-7-iodo-2-methylindenyl-3-acetate	2-Chloro-5-methyl-9-(p-methylthiobenzylidene)-cyclopenta[j,k]-phenanthrene-4-acetic acid
6. 4-Chloro-2-nitrobenzoic acid	4-Methylthio-2-iodobenzaldehyde	6-Acetyl-2-methylindanone	Methyl 5-acetyl-7-iodo-2-methylindenyl-3-acetate	2-Acetyl-5-methyl-9-(p-methylthiobenzylidene)-cyclopenta[j,k]-phenanthrene-4-acetic acid
7. 4-Chloro-2-nitrobenzoic acid	4-Methylthio-2-iodobenzaldehyde	6-Vinyl-2-methylindanone	Methyl 5-vinyl-7-iodo-2-methylindenyl-3-acetate	2-Vinyl-5-methyl-9-(p-methylthiobenzylidene)-cyclopenta[j,k]-phenanthrene-4-acetic acid

EXAMPLE 8

2-Fluoro-5-methyl-9-(p-methylsulfinylbenzylidene)-cyclopenta[j,k]-phenanthrene-4-acetoxy- β -D-glycopyranosiduronic acid

Sodium methoxide (25% solution 30 ml.) is added to a stirred solution of 2-fluoro-9-(p-methylsulfinylbenzylidene)-cyclopenta[j,k]-phenanthrene-4-acetic acid (0.13 M) in tetrahydrofuran (800 ml.). The precipitate is filtered off and dried at 60° under vacuum.

Methyl (tri-O-acetyl- α -D-glucopyranosylbromide)-uronate is made according to a procedure described in J. Amer. Chem. Soc. 77 3310 (1955) or J. Amer. Chem. Soc. 82 2827 (1960).

The dry sodium salt (0.1 M) and the bromopyranoside (0.12 M) are heated in dry dimethyl sulfoxide with stirring at 60° for 2 hours. The product is used as is, the free acid, is a biproduct of the next reaction.

The crude product in dimethoxyethane (125 ml.) and 2.5N hydrochloric acid (62.5 ml.) is heated to 90° for 3 hours. The solution is evaporated at 70° to one-half volume and extracted with methylene chloride (2 $\times$ 30 ml.). The solution is then saturated with sodium chloride and extracted with methylene chloride again (30 ml.), then ethyl acetate (2 $\times$ 50 ml.) and this last extraction washed with water (20 ml.), dried (anhydrous magnesium sulfate), filtered and evaporated to dryness. In this way the glucoronide is isolated from the starting material.

Similarly when an equivalent amount of 2-fluoro-5-methyl-9-(p-methylsulfinylbenzylidene)-cyclopenta[j,k]-phenanthrene-4- α -propionic acid or the substituted phenanthrene-4-acetic acids obtained from Examples 5 to 7 are used in place of 2-fluoro-5-methyl-9-(p-methylsulfinylbenzylidene)cyclopenta[j,k]-phenanthrene-4-acetic acid in the above example, there are obtained the corresponding β -D-glucopyranosiduronic acid compounds.

EXAMPLE 9

2-Fluoro-5-methyl-9-(p-methylsulfinylbenzylidene)-cyclopenta[j,k]-phenanthrene-4-acetic acid anhydride

A solution of 0.05 mole of N,N'-dicyclohexyl carbodiimide in 60 ml. of tetrahydrofuran is added to 0.05 mole of 2-fluoro-5-methyl-9-(p-methylsulfinylbenzylidene)-cyclopenta[j,k]-phenanthrene-4-acetic acid in 25 ml. of tetrahydrofuran. The reaction mixture is shaken vigorously at about 25° for 16 hours. The dicyclohexylurea is filtered off and 2 ml. of glacial acetic acid is added to the filtrate. The solution is allowed to stand for 1 hour, filtered and 200 ml. of ether added to the filtrate. The filtrate is then extracted well with water, dried and concentrated. The desired product is purified by column chromatography on silica gel using ether-petroleum ether as an eluent.

Similarly when an equivalent amount of 2-fluoro-5-methyl-9-(p-methylsulfinylbenzylidene)-cyclopenta[j,k]-phenanthrene-4- α -propionic acid or the other substituted phenanthrene-4-acetic acids obtained from Examples 5 to 7 are used in place of 2-fluoro-5-methyl-9-(p-methylsulfinylbenzylidene)-cyclopenta[j,k]-phenanthrene-4-acetic acid, there are obtained the corresponding anhydrides.

EXAMPLE 10

Esters

of

2-fluoro-5-methyl-9-(p-

methylsulfinylbenzylidene)-cyclopenta[j,k]-phenanthrene-4-acetic acids

(A) Simple Esters — A mixture of .1 mole of 2-fluoro-5-methyl-9-(p-methylsulfinylbenzylidene)-cyclopenta[j,k]-phenanthrene-4-acetic acid, .2 g. of p-toluenesulfonic acid, 100 ml. of absolute ethanol and 75 ml. of dry benzene is refluxed on a steam bath while slowly distilling the solvent. After 17 hours, the residual solvent is removed under reduced pressure. The residue is slurried in aqueous sodium bicarbonate and then with water until neutral. The resulting ethyl ester may be recrystallized from organic solvents such as ethyl acetate, benzene and the like.

When methanol, propanol, t-butanol and benzyl alcohol are used instead of the ethanol in the above procedure, there is obtained the corresponding methyl, propyl, t-butyl and benzyl esters.

(B) Alkoxyalkyl Esters — Chloromethyl methyl ether (0.055 mole) is added to a suspension of 2-fluoro-5-methyl-9-(p-methylsulfinylbenzylidene)-cyclopenta[j,k]-phenanthrene-4-acetic acid (0.05 mole) and anhydrous potassium carbonate (0.15 mole) in 250 ml. of anhydrous acetone. The mixture is allowed to stir overnight at room temperature. Diethyl ether is added (about 200 ml.) and the mixture is filtered. The filtrate is washed once with 100 ml. of water and dried over anhydrous sodium sulfate. It is then filtered and the solvent is removed in vacuo. The residue is chromatographed on 200 g. of acid-washed alumina, using ether-petroleum ether (varying from 10 to 60% ether by volume) as the eluent, to give methoxymethyl 2-fluoro-5-methyl-9-(p-methylsulfinylbenzylidene)-cyclopenta[j,k]-phenanthrene-4-acetate.

(C) Phenyl 2-fluoro-5-methyl-9-(p-methylsulfinylbenzylidene)-cyclopenta[j,k]-4-acetate — A solution of 0.0054 mole of N,N'-dicyclohexyl carbodiimide in 6 ml. of anhydrous tetrahydrofuran is added to a solution of 2-fluoro-5-methyl-9-(p-methylsulfinylbenzylidene)-cyclopenta[j,k]-phenanthrene-4-acetic acid (0.005 mole) and phenol (0.0054 mole) in 17 ml. of anhydrous tetrahydrofuran. The mixture is shaken vigorously and allowed to sit, stoppered, at room temperature overnight.

After filtering off the N,N'-dicyclohexylurea, 2 ml. of glacial acetic acid is added to the filtrate and the mixture allowed to stand one hour. After filtering, 200 ml. ether is added to the filtrate and the ether solution and 3 $\times$ 100 ml. water and then dried over anhydrous sodium sulfate. The mixture is filtered, concentrated in vacuo to 25 ml. and chromatographed on a 150 g. acid washed alumina column using ether-petroleum ether (v/v, 10°-60°) as eluent to give phenyl 2-fluoro-5-methyl-9-(p-methylsulfinylbenzylidene)-cyclopenta[j,k]-phenanthrene-4-acetate.

Similarly using 2-(2-methoxyethoxy)-ethanol, glycol or N-acetyl-ethanolamine in place of phenol in the above procedure gives (2'-(2''-methoxyethoxy)-ethyl)-2-fluoro-5-methyl-9-(p-methylsulfinylbenzylidene)-cyclopenta[j,k]-phenanthrene-4-acetate, β -hydroxyethyl 2-fluoro-5-methyl-9-(p-methylsulfinylbenzylidene)-cyclopenta[j,k]-phenanthrene-4-acetate and β -acetamidoethyl 2-fluoro-5-methyl-9-(p-methylsulfinylbenzylidene)-cyclopenta[j,k]-phenanthrene-4-acetate, respectively.

Similarly when 2-fluoro-5-methyl-9-(p-methylsulfinylbenzylidene)-cyclopenta[j,k]-phenanthrene-4- α -propionic acid or the other substi-

tuted phenanthrene acetic acids obtained from Examples 5 to 7 are used in place of the above-described acid in any of the above preparations, the corresponding esters are obtained.

EXAMPLE 11

Pivalloyloxymethyl-2-fluoro-5-methyl-9-(p-methylsulfinylbenzylidene)-cyclopenta[j,k]-phenanthrene-4-acetate

Trimethylamine (1.2 gm.) in dimethylformamide (10 ml.) is added over 5 minutes to a stirred solution of the 2-fluoro-5-methyl-9-(p-methylsulfinylbenzylidene)-cyclopenta[j,k]-phenanthrene-4-acetic acid (0.01 mole) in dimethylformamide (100 ml.) at room temperature. After 10 minutes pivalloyloxymethylchloride (1.9 g.) is added in dimethylformamide (10 ml.). The stirred solution is kept at 90° for 18 hours, poured into water (300 ml.) and extracted with ether (2 × 300 ml.). The ether extract is washed with sodium hydroxide solution (2.5N, 50 ml.), water (50 ml.), separated and dried (anhydrous magnesium sulfate). The crude product, isolated by evaporation, is purified by column chromatography on silica gel (Baker 80-100 mesh) in a 2 ft. × 1 in. column, eluting with methylene chloride.

The product isolated in this way is recrystallized from benzene-n-hexane.

Similarly when an equivalent amount of 2-fluoro-5-methyl-9-(p-methylsulfinylbenzylidene)-cyclopenta[j,k]-phenanthrene-4- α -propionic acid or the substituted phenanthrene-4-acetic acids obtained from Examples 5 to 7 is used in place of 2-fluoro-5-methyl-9-(p-methylsulfinylbenzylidene)-cyclopenta[j,k]-phenanthrene-4-acetic acid above, there is obtained the corresponding pivalloyloxymethyl esters.

EXAMPLE 12

2-Fluoro-5-methyl-9-(p-methylsulfinylbenzylidene)-cyclopenta[j,k]-phenanthrene-4-acetmorpholide

A mixture of 2-fluoro-5-methyl-9-(p-methylsulfinylbenzylidene)-cyclopenta[j,k]-phenanthrene-4-acetic acid (0.01 mole) and thionyl chloride (0.03 mole) in a dried flask, condenser and drying tube set-up is heated on the steam bath until evolution of gas ceases. Excess thionyl chloride is then removed in vacuo, the residue taken up in a slight excess of anhydrous ether and added slowly to a vigorously stirred, ice-cooled solution of dry morpholine (0.035 mole) in 100 ml. of ether. The mixture is stirred overnight at room temperature, filtered, the morpholine hydrochloride washed with 2 × 100 ml. water, dried over anhydrous sodium sulfate, filtered and the ether removed in vacuo. Chromatography of the crude product on a silica-gel column, using v/v. 50-100% ether in petroleum ether as eluent gives the desired morpholide.

Similarly when morpholine is replaced by an equivalent amount of the following amines, the corresponding amides are obtained:

Dimethylamine

Ethanolamine

Benzylamine

N,N-diethylethylenediamine

Benzylglycinate

Piperidine

Pyrrolidine

N-methylpiperazine

N-phenylpiperazine
N-hydroxyethylpiperazine

Piperazine

Diethylamine

Diethanolamine

Aniline

p-Ethoxyaniline

p-Chloroaniline

p-Fluoroaniline

p-Trifluoromethylaniline

Butylamine

Cyclohexylamine

Methylamine

D-glucosamine

Tetra- α -acetyl-d-glucosamine

D-galactosylamine

D-mannosylamine

N,N-dimethyl-glycine amide

N,N-dibutylglycine amide

β -ethoxyethylamine

Di(β -ethoxyethyl)amine

B-Phenethylamine

Dibenzylidene

D-mannosamine

Similarly when an equivalent amount of 2-fluoro-5-methyl-9-(p-methylsulfinylbenzylidene)-cyclopenta[j,k]-phenanthrene-4- α -propionic acid or the substituted phenanthrene-4-acetic acids obtained from Examples 5 to 7 are used in place of the 2-fluoro-5-methyl-9-(p-methylsulfinylbenzylidene)-cyclopenta[j,k]-phenanthrene-4-acetic acid in the above example, there is obtained the corresponding morpholide compounds.

EXAMPLE 13

N-[2-fluoro-5-methyl-9-(p-methylsulfinylbenzylidene)-cyclopenta[j,k]-phenanthrene-4-acetoxy]-glycine

A. **Benzyl-N-[2-fluoro-5-methyl-9-(p-methylsulfinylbenzylidene)-cyclopenta[j,k]-phenanthrene-4-acetoxy]-glycinate** — The procedure of Example 12 is followed using benzylamino acetate in place of the morpholine to produce the above-named compound.

B. **Benzyl-N-[2-fluoro-5-methyl-9-(p-methylsulfinylbenzylidene)-cyclopenta[j,k]-phenanthrene-4-acetoxy]-glycinate** (0.003 mole) in a mixture of 25 ml. of anhydrous ethanol and 2.5 ml. of 1 N sodium hydroxide is allowed to stand at room temperature for 18 hours. The solution is diluted with water and extracted with ether. The aqueous layer is acidified with dilute hydrochloric acid and the organic product is extracted with ethyl acetate, washed with water and dried over sodium sulfate. Evaporation of the solution gives **N-[2-fluoro-5-methyl-(p-methylsulfinylbenzylidene)-cyclopenta[j,k]-phenanthrene-4-acetoxy]-glycine**.

60 When an equivalent amount of 2-fluoro-5-methyl-9-(p-methylsulfinylbenzylidene)-cyclopenta[j,k]-phenanthrene-4- α -propionic acid or the substituted phenanthrene-4-acetic acids obtained from Examples 5 to 7 are used in place of the 2-fluoro-5-methyl-9-(p-methylsulfinylbenzylidene)-cyclopenta[j,k]-phenanthrene-4-acetic acid in the above example, there is obtained the corresponding glycine compound.

EXAMPLE 14

Sodium 2-fluoro-5-methyl-9-(p-methylsulfinylbenzylidene)-cyclopenta[j,k]-phenanthrene-4-acetate

A mixture of 0.030 moles of 2-fluoro-5-methyl-9-(p-methylsulfinylbenzylidene)-cyclopenta[j,k]-phenanthrene-4-acetic acid and 0.033 moles of sodium methoxide (25% solution in water) 7.4 ml. in 200 ml. of tetrahydrofuran is stirred for 2 hours at 0°C. The reaction mixture is filtered and the product dried to yield the subject compound.

Similarly when an equivalent amount of calcium hydride or potassium methoxide is used in place of sodium methoxide in the above example, there is obtained the corresponding calcium or potassium salt.

Similarly when 2-fluoro-5-methyl-9-(p-methylsulfinylbenzylidene)-cyclopenta[j,k]-phenanthrene-4- α -propionic acid or the other substituted phenanthrene-4-acetic acids obtained from Examples 5 to 7 are used in place of 2-fluoro-5-methyl-9-(p-methylsulfinylbenzylidene)-cyclopenta[j,k]-phenanthrene-4-acetic acid in the above example, there is obtained the corresponding sodium salts of the compounds.

EXAMPLE 15

A mixture of 260 parts of 2-fluoro-5-methyl-9-(p-methylsulfinylbenzylidene)-cyclopenta[j,k]-phenanthrene-4-acetic acid and 25 parts of lactose is granulated with suitable water and to this is added 100 parts of maize starch. The mass is passed through a 16 mesh screen. The granules are dried at a temperature below 60°C. The dry granules are passed through a 16 mesh screen and mixed with 3.8 parts of magnesium stearate. They are then compressed into tablets suitable for oral administration.

Similarly, tablets are prepared by employing an equivalent amount of the substituted phenanthrene-4-acetic acid obtained from Examples 5 to 7 or the corresponding esters, anhydrides or amides obtained from Examples 8 to 13.

What is claimed is:

1. The compound of the formula:

wherein:

R₁ and R₂ are each hydrogen or lower alkyl;

R₃ is hydrogen, C₁₋₅ alkyl, halo, halo C₁₋₅ alkyl, phenyl, C₁₋₅ alkylthio, phenylthio, C₂₋₅ alkenyl, C₁₋₅ alkoxyphenyl, trifluoromethyl or benzyl;

R₄ is hydrogen, trifluoromethyl, halo, C₁₋₅ alkyl, phenyl, benzyl;

R₅ is hydrogen, hydroxy, halo, C₁₋₅ alkylthio, benzylxy, C₁₋₅ alkylsulfinyl, C₁₋₅ dialkylsulfonyl, C₁₋₅ dialkylamino-C₁₋₅ alkyl, C₁₋₅ alkylbenzyloxy, benzylthio, C₁₋₅ dialkylamino, halobenzyloxy, C₁₋₅ alkoxy, C₁₋₅ alkyl, C₁₋₅ alkylsulfamyl, C₂₋₅ alkanoyloxy, phenoxy, C₂₋₅ alkenyl, C₂₋₅ alkenyloxy or benzyl;

R₆ is hydrogen, C₂₋₅ alkenyl, halo, C₁₋₅ alkoxy, C₁₋₅ alkyl, benzyloxy or C₁₋₅ alkylthio; at least one of R₄, R₅ or R₆ is hydrogen at any one time;

R₇ is hydrogen, C₁₋₅ alkylthio, C₁₋₅ alkylsulfinyl or C₁₋₅ alkylsulfonyl;

R₈ is hydrogen, halo, hydroxy, C₁₋₅ alkoxy, halo C₁₋₅ alkyl, phenyl, C₁₋₅ alkanoylamino or C₁₋₅ alkanoyl; and

M is hydroxy, C₁₋₅ alkoxy or pivalyloxy.

2. The compound of claim 1 wherein:

R₁ and R₂ are each hydrogen;

R₃ is C₁₋₅ alkyl;

R₄ is hydrogen;

R₅ is hydrogen, C₁₋₅ dialkylamino, halo, C₁₋₅ alkanoyloxy, C₂₋₅ alkenyl or C₂₋₅ alkenyloxy;

R₆ is hydrogen or halo;

R₇ is halo, C₁₋₅ alkylthio or C₁₋₅ alkylsulfinyl;

R₈ is hydrogen; and

M is hydroxy.

3. The compound of claim 2 wherein:

R₁ and R₂ are each hydrogen;

R₃ is methyl;

R₄ is hydrogen;

R₅ is dimethylamino, allyloxy, chloro, acetyl, fluoro or vinyl;

R₆ is hydrogen;

R₇ is methylthio;

R₈ is hydrogen; and

M is hydroxy.

4. The compound of claim 2 wherein:

R₁ and R₂ is hydrogen;

R₃ is methyl;

R₄ is hydrogen;

R₅ is hydrogen;

R₆ is fluoro;

R₇ is fluoro;

R₈ is hydrogen; and

M is hydroxy.

5. The compound of claim 2 wherein:

R₁ and R₂ is hydrogen;

R₃ is methyl;

R₄ is hydrogen;

R₅ is fluoro;

R₆ is hydrogen;

R₇ is methylsulfinyl;

R₈ is hydrogen; and

M is hydroxy.
